(57) **CLAIM**

The ornamental design for a toothbrush holder, as shown and described.

DESCRIPTION

FIGS. 1 and 2 are perspective views of my new design;
FIG. 3 is a top plan view thereof;
FIG. 4 is a front elevational view thereof;
FIG. 5 is a rear elevational view thereof;
FIG. 6 is a bottom plan view thereof;
FIG. 7 is a left side elevational view thereof;
FIG. 8 is a right side elevational view thereof;
FIG. 9 is a perspective view of a first alternate embodiment
of my new design; and,
FIG. 10 is a perspective view of a second alternate embodiment
of my new design.

The broken lines shown in the drawing figures are for
illustrative purposes only and form no part of the claimed
design.
